UNITED STATES PATENT OFFICE.

GEORGE A. WHITE, OF JACKSON, MICHIGAN.

DESIGN FOR A SIGNALING DEVICE.

Application filed May 3, 1927. Serial No. 21,840. Term of patent 3½ years.

To all whom it may concern:

Be it known that I, GEORGE A. WHITE, a citizen of the United States, residing in the city and county of Jackson, Michigan, have invented a new, original, and ornamental Design for a Signaling Device, of which the following is a specification, reference being had to the accompanying drawings, forming part thereof.

Figure 1 is a top plan view of the signaling device.

Figure 2 is a side elevation of the same.

Figure 3 is a rear elevation of the same.

I claim:

The ornamental design for a signaling device substantially as shown and described.

GEORGE A. WHITE.
